DESIGN FOR A COMBINED LAPEL PIN AND MATCH BOOK HOLDER

Louise H. Thomas, New York, N. Y.

Application May 20, 1938, Serial No. 77,304

Term of patent 3½ years

To all whom it may concern:

Be it known that I, Louise H. Thomas, a citizen of the United States of America, residing at 2 Beekman Place, in the Borough of Manhattan, city, county, and State of New York, have invented a new, original, and ornamental Design for a Combined Lapel Pin and Match Book Holder, of which the following is a specification, reference being had to the accompanying draw-

ing, forming a part thereof, and showing in Fig. 1 a perspective front view and in Fig. 2 a perspective rear view of the combined lapel pin and match book holder embodying my design.

I claim:

The ornamental design for a combined lapel pin and match book holder, substantially as shown.

LOUISE H. THOMAS.
